LEAD PENCIL

August Leistenschneider, Dusseldorf, Germany

Application January 29, 1934, Serial No. 708,801
In Germany January 31, 1933

13 Claims. (Cl. 120—17)

The present invention relates to a mechanical or magazine lead pencil, and particularly to one of the type in which the lead is advanced by longitudinal or axial movement of a cap or operating member accessible at the exterior of the pencil. The invention is, in some respects, a modification of and an improvement upon the pencil construction disclosed in United States Patent No. 1,969,085, granted Aug. 7, 1934, for a joint 5 invention of August Leistenschneider and Konrad Kressel.

An object of the invention is the provision of a generally improved and more satisfactory pencil of this type.

Another object is the provision, in a pencil of this kind, of improved lead gripping or clamping means, and particularly of such means designed so that the lead may be gripped relatively close to the writing point or end thereof, and so that, 10 when the gripping means releases the lead, it will release it positively and completely, without binding or dragging on the lead.

To these and other ends the invention resides in certain improvements and combinations of 15 parts, all as will be hereinafter more fully described, the novel features being pointed out in the claims at the end of the specification.

In the accompanying drawing:

Fig. 1 shows a mechanical lead pencil according to the invention in longitudinal section.

Fig. 2 shows a magazine for lead pencils according to the invention in longitudinal section.

Referring to the drawing, the lead is gripped near the tip of the pencil by a clamping sleeve indicated in general at 6, this sleeve being split longitudinally through part or, preferably, all of its length, to form a plurality of gripping or clamping fingers. The extreme lower or forward ends of the fingers have exterior surfaces which 20 are of generally conical shape, converging steeply or sharply toward their lower ends, as indicated at 4, which surfaces may be described as being tapered downwardly, or as growing smaller in a downward or forward direction. Rearwardly or above the downwardly tapered portion, these fingers have a portion the exterior surfaces of which are of generally conical shape converging toward their upper ends, the convergence being less steep or sharp than that of the downwardly 25 tapered lower ends, as plainly shown in Fig. 1. This portion which converges upwardly or grows smaller in a rearward direction may be said to be tapered rearwardly, and at the upper end of this portion is a sharp or abrupt inward offset, step 30 or ledge 2. From this step 2 to a point near the

rear ends of the clamping fingers, the exterior surfaces of the fingers may be substantially cylindrical, as shown, and the rear ends of the fingers are loosely hung at the lower end of the lead tube 8, in a manner similar to or identical with the manner in which the fingers 19 and 20 are hung in said Patent No. 1,969,085.

The inner surfaces of the fingers 6, near their forward ends, are of arcuate cross section and of a radius substantially equal to that of the lead intended to be used in this pencil. Near the middle of the length of the fingers, the inner surfaces of the fingers are conical, inclining or sloping obliquely outwardly and rearwardly, as shown, and thence the inner surfaces continue rearwardly with a cross sectional radius sufficiently large so as not to bear against the lead to any substantial extent. Hence, when the clamping fingers are moved radially inwardly toward each other, by the clamping ring hereafter described, the fingers will grip a stick of lead extending centrally through the fingers, and this gripping will take place at and near the lower ends of the fingers but not at the upper ends of the fingers, where the diameter of the internal space through the fingers is greater than that of the lead. The fingers preferably grip the lead throughout an axial extent or length of at least 15 times the diameter of the lead.

The clamping ring, for operating the fingers of the clamping sleeve 6 to grip or release the lead, is indicated in general at 4. Intermediate its length, the ring has a shoulder 8, and a substantially cylindrical tubular portion of larger diameter extends rearwardly from this shoulder, terminating in an outwardly extending annular flange 6. A coiled spring 5, surrounding this part of the clamping ring, presses rearwardly on the flange 6 and constantly tends to move the clamping ring rearwardly until the upper or rearward surface 8' of the flange 6 comes into contact with the front surface 7' of a block or member 7 secured in fixed position in the pencil casing, and preferably split longitudinally into two parts, for ease of assembly. From the shoulder 8, another tubular portion of the clamping ring, of smaller cross-sectional diameter than the first mentioned portion, extends forwardly to a forward end or edge 3. This last mentioned tubular portion at its forward end has its inner surface conically shaped to be substantially complementary to and cooperate with the conical outer surfaces of the fingers immediately forwardly of the shoulder 2, as will be readily seen from the drawing. If the clamping ring be moved forwardly relatively to

the clamping fingers, the ring will force the fingers radially inwardly toward each other to grip an interposed lead. If the ring be moved rearwardly relatively to the fingers, the fingers will be released from the lead, gradually at first, and then when the forward end 3 of the ring moves rearwardly beyond the shoulder 2 of the fingers, the fingers will be suddenly further released to an even greater extent, so that they may swing wide apart and completely release the lead, exerting no drag upon it.

The front end of the pencil is provided with a nose piece or casing 11, preferably of resilient metal and longitudinally split at its forward end. It will be noted from the drawing that the cavity or chamber within this nose piece 11 is of sufficient diameter to accommodate the lead clamping parts, almost to the extreme end of the pencil, thus enabling the clamping parts to be brought very close to the writing end of the lead. Yet, with the design here shown, this does not make the exterior of the nose piece of awkward size or shape. The exterior of the nose piece may be of decreasing size in a forward direction, as shown, and may be described as tapered forwardly. A shoulder 10 within the nose piece contacts with the shoulder 8 of the clamping ring to limit forward movement of the ring.

To reduce the cost of production, it is desirable to make the clamping fingers and clamping ring of a soft, easily workable metal, such, for example, as brass, aluminum, duraluminum, German silver, copper, or alloys of such metals. According to the present invention, those parts of the soft metal which are exposed to strong friction, such as the parts marked 47 and 48 in Fig. 1, have applied to them coating or covering layers 49 and 50 of a hard wear-resisting metal, which preferably is also resistant to acids and non-rusting. Suitable metals for this purpose are nickel, chromium, tungsten, iridium, platinum, palladium, molybdenum, and the like. These wear-resisting coatings or linings greatly increase the life of the clamping parts, without unduly increasing the cost of construction.

As above stated, the clamping fingers 6 are loosely connected to or hung from the forward end of the lead tube 9. This lead tube has a shoulder 17 cooperating with the surface 18 of the stationary member 7, to limit rearward movement of the tube so that the clamping fingers cannot be drawn too far rearwardly through the clamping ring when the ring is already at the rearward limit of its motion, particularly when there is no lead in the tube, thus avoiding jamming and injury of the parts. The tube also has a shoulder 19 cooperating with a surface 16 on the stationary member 7, to limit forward movement of the tube and prevent the feeding fingers from being jammed against the front wall of the nose piece 11. To the extent permitted by these shoulders 17 and 19, the lead tube 9 may move longitudinally within the pencil casing, and is constantly urged rearwardly by a coiled spring 9' which presses at its forward end against the stationary member 7 and at its rear end against the lead tube or some part connected thereto, such as the member 27.

In the preferred form of construction, the member 27 is divided longitudinally into two pieces, for ease of assembly, and constitutes the bottom of a lead magazine or reservoir. The side walls 22 of the magazine are fixed, as by means of an annular groove 28, to the bottom member

27. The magazine is slideable axially or longitudinally within the main metal casing member or tube 21, which may be surrounded by an exterior sheath or sleeve 20 of any suitable material, such as an artificial mass. The upper end of the magazine walls 22 may be provided with a screw thread 23, for engaging a threaded annular member 24 the upper end of which is closed by a plug 25 having an annular flange 26 which may be conveniently grasped for unscrewing the members 10 24 and 25 from the magazine walls 22. When the closure is thus unscrewed, the interior space 30 of the lead magazine may be filled with leads, which will rest on the conical surface 29 of the bottom member 27, and one at a time the leads 15 will fall into and fill the space 31 within the lead tube 9.

Frequently it is desirable not to fix the magazine bottom 27 rigidly to the lead tube 9, but to provide for some relative movement between 20 these parts at each feeding operation, so as to disturb the leads within the magazine and prevent them from jamming therein. To this end, annular flanges 32 and 33 may be formed on the tube 9, the flange 32 being located within an annular recess in the member 27, which recess has a rear end 34 and a forward end 35. The forward limit of movement of the tube 9 relative to the magazine member 27 is defined by contact of the flange 32 with the surface 35, while the rearward limit of relative movement is defined by contact of the flange 33 with the front end of the member 27 and simultaneous contact of the flange 32 with the surface 34, thus giving a good bearing on two parts so that too heavy a stress on a small area of the tube 9 during a forward feeding operation is avoided. When the tube 9 moves rearwardly relatively to the magazine bottom 27, upon pushing down on the cap 26, a projection 36 on one side of the rear end of the tube 9, shaped somewhat like the point of a shovel, enters the lead space 30 in the magazine and disturbs the leads therein, pushing aside any leads blocking the filling opening and facilitating the sliding of a single lead 45 into the filling tube 9.

The form of the lead pencil described may be altered in different ways within the scope of the present invention.

Working of the pencil

The pencil described works as follows:—When the pencil-cap 26 is pressed forwards in the direction of the point, the filling-tube 9 moves also towards the point. As shown in Fig. 1, the position of the filling-tube is between the resting position of the cap and its completed forward movement. When the cap is pressed farther forward, the filling-tube 9 together with the clamping-sleeve 6 and the clamping-ring 60 4 held firmly thereto by adhesion and holding the said clamping-sleeve together, is pressed forward until the shoulder 8 rests upon the projection 10.

Further forward movement of the tube 9, caused by further pushing upon the cap 26, causes the clamping sleeve 6 to slide forwardly through the clamping ring 4, since the ring can not move any farther forwardly. The frictional adhesion between the sleeve and the ring is thus gradually lessened, until it is overcome by the force of the spring 8, which then returns the clamping ring to its rearmost position, thus completely releasing the clamping fingers from the lead and permitting the fingers to spread far 75

apart so that they will not bind or drag on the lead when they move rearwardly.

The cap 26 is then released, and the spring 9' moves the cap, the tube 9, and the clamping sleeve 0 rearwardly, without changing the position of the lead. During this movement, the fingers of the clamping sleeve are drawn rearwardly through the clamping ring, which cannot move any farther rearwardly, and near the end 10 of this rearward movement the relative motion between the fingers and the ring causes the fingers to clamp upon the lead, holding it firmly for writing until further advancement of the lead is needed. Then, when feeding is desired, 15 forward movement of the cap 26 moves the tube 9 and the clamping fingers 0 forwardly, the clamping ring 4 adhering frictionally to the fingers and moving forwardly with them against the force of the spring 5, so that the fingers 20 remain tightly clamped on the lead and advance the lead, until the fingers are released near the forward end of the movement, as above explained.

It is now seen that an improved pencil has 25 been provided, in which the lead is effectively gripped and completely released at the proper time. With this improved design and construction, the lead is gripped much closer to the nose of the pencil than in the prior construction illustrated in said Patent No. 1,969,085, with the result that less lead is wasted at the end of each piece or stick, and the lead is held more satisfactorily. Also, in this improved construction the lead is released more completely and satisfactorily than in the prior construction, so that all danger of accidental rearward movement of the lead is avoided.

Another advantage of the present improved construction is that the nose piece 11 may be 40 readily removed for cleaning the clamping fingers, when required, without causing any of the other parts to become loose or fall out. It is seen from Fig. 1 that the nose piece is screwed onto the forward end of the main casing parts. 45 When it is unscrewed and removed therefrom, the clamping fingers are readily accessible for cleaning, especially if they be pushed forwardly by pressure on the cap 26. In spite of the removal of the shoulder 10 of the nose piece out 50 of the path of the shoulder 8 on the clamping ring, the clamping ring still can not drop out, as it is held in place by its flange or shoulder 6, which can not pass through the front of the casing.

55 Certain features disclosed but not claimed herein, and particularly the construction of the lead magazine, are claimed in my companion application for Magazine for lead pencil, Serial No. 708,802, filed January 29, 1934.

60 I claim:

1. A mechanical pencil comprising a casing having a nose of external cross sectional dimensions decreasing toward its forward end, said nose having therein a cavity having a portion of 65 internal cross sectional dimensions decreasing toward said forward end with the smaller end of said portion of said cavity closely adjacent said forward end of said nose, lead grasping means mounted for forward and backward reciprocation within said casing, said grasping means including a plurality of fingers movable laterally toward and away from a lead and having terminal portions with external dimensions decreasing toward their forward ends so that when said fingers 70 are reciprocated forwardly said terminal portions

may lie within said portion of said cavity closely adjacent said forward end of said nose, and means for closing said fingers upon a lead near the rear end of a reciprocation of said fingers and releasing said fingers from said lead near the forward end of a reciprocation. 5

2. A mechanical pencil comprising a casing having a nose at least partially tapered toward its forward end, said nose having therein a cavity having a portion also tapered with the smaller 10 end of said portion of said cavity closely adjacent said forward end of said nose, lead grasping means mounted for forward and backward reciprocation within said casing, said grasping means including a plurality of fingers movable laterally toward and away from a lead and having terminal portions tapered toward their forward ends so that when said fingers are reciprocated forwardly said terminal portions may lie within said tapered portion of said cavity closely 15 adjacent said forward end of said nose, said fingers also having rearwardly of said terminal portions other portions which are tapered rearwardly, and a movable clamping member surrounding said fingers and adapted to cooperate with said rearwardly tapered portion to wedge 20 said fingers into gripping relation to a lead. 25

3. A mechanical pencil comprising a casing having a nose whose external sides converge toward its forward end, said nose having therein a cavity having a portion shaped to contract toward said forward end with the smaller end of said portion of said cavity closely adjacent said forward end of said nose, lead grasping means 30 mounted for forward and backward reciprocation within said casing, said grasping means including a plurality of fingers movable laterally toward and away from a lead and having terminal portions whose external sides converge toward their forward ends so that when said 35 fingers are reciprocated forwardly said terminal portions may lie within said converging portion of said cavity closely adjacent said forward end of said nose, said fingers also having, rearwardly 40 of said terminal portions, other portions with outer sides diverging gradually toward said forward ends and relieved suddenly at their rear ends, and a clamping ring surrounding said fingers and adapted to cooperate with said diverging portion to clamp said fingers upon a lead and to move off of said diverging portions past the relieved ends thereof to unclamp said fingers 45 and free them for substantial movement away from a lead. 50

4. A mechanical pencil comprising a casing, a tube mounted for reciprocation within said casing, a plurality of lead-engaging fingers operatively connected to said tube and extending forwardly therefrom, and a clamping member also 60 movable within said casing, said clamping member including a tubular portion of one size cooperating with said fingers to cause them to clamp a lead and a tubular portion of a different size extending rearwardly and at least partially 65 encircling said tube near its forward end.

5. A mechanical pencil comprising a casing, a tube mounted for reciprocation within said casing, a plurality of lead-engaging fingers operatively connected to said tube and extending forwardly therefrom, a clamping member also movable within said casing, said clamping member including adjacent its forward end a tubular portion of smaller size at least partially encircling 70 said fingers and cooperating with them to cause 75

them to clamp a lead and including adjacent its rear end a tubular portion of larger size at least partially encircling said tube near the forward end thereof, and means fixed relatively to said casing and located rearwardly of said larger sized tubular portion and serving as an abutment to limit rearward movement of said clamping member.

6. A construction according to claim 5, further 10 including a spring surrounding said rearwardly extending portion of said clamping member and operatively connected thereto to tend to move said clamping member in a rearward direction.

7. A mechanical pencil comprising a casing, a 15 plurality of lead-engaging fingers mounted for forward and backward movement within said casing, said fingers having portions tapered externally in a rearward direction, abutment means within said casing, and a finger clamping member 20 movably mounted in said casing, said member including a portion of smaller transverse dimension extending forwardly for cooperation with said fingers to cause them to clamp a lead, and a portion of larger transverse dimension extending rearwardly for cooperation with said 25 abutment means to limit rearward movement of said member.

8. A mechanical pencil comprising a casing, a 30 plurality of lead-engaging fingers mounted for forward and backward movement within said casing, said fingers having portions with exterior surfaces diverging in a forward direction, and a member surrounding said fingers and shaped internally to cooperate with said diverging portions of said fingers and capable of relative longitudinal movement with respect to said fingers, so that when said member is moved forwardly with respect to said diverging portions of said fingers, said fingers will be contracted to clamp 35 upon a lead, and when said member is moved rearwardly with respect to said diverging portions of said fingers, said fingers may expand to free a lead, said fingers being suddenly relieved at the rear ends of said diverging portions so 40 that when said member is moved beyond said rear ends of said diverging portions said fingers may expand to a materially greater extent.

9. A mechanical pencil comprising a casing, a 45 plurality of lead-engaging fingers mounted for forward and backward movement within said casing, said fingers throughout portions of their lengths having exterior surfaces diverging in a forward direction and thence converging substantially from said diverging portions to their 50 forward ends, so that said forward ends may lie closely adjacent the forward end of the pencil, and a member surrounding said fingers and shaped internally to cooperate with said diverging portions thereof, to cause a clamping action 55 of said fingers upon a lead and to allow release thereof.

10. A mechanical pencil comprising a casing, a 60 tube mounted for reciprocation within said casing, a plurality of lead-engaging fingers operatively connected to said tube and extending forwardly therefrom, a clamping member also movable within said casing for cooperation with

said fingers to cause them to clamp upon a lead and to release them therefrom, and a member secured in said casing rearwardly of said clamping member and serving both as an abutment for limiting rearward movement of said clamping member and as an abutment for limiting 5 forward movement of said tube.

11. A mechanical pencil comprising a casing having a main portion and a removable nose portion, a plurality of lead-grasping fingers 10 mounted for movement back and forth within said casing, said fingers when in their most advanced position normally lying at least partially within said removable nose portion so that said fingers may be rendered accessible for inspection and cleaning by removal of said nose portion, a clamping ring also mounted within said casing for movement back and forth with relation to said fingers to cause said fingers to grasp and release a lead, and means other than 15 said fingers themselves for preventing removal of said clamping ring from said casing in a forward direction notwithstanding removal of said nose portion.

12. A mechanical pencil comprising a main 20 casing, a lead holding tube mounted for reciprocation within said casing, a plurality of lead clamping fingers loosely mounted on said tube and projecting forwardly therefrom beyond the forward end of said main casing, a clamping 25 ring having a portion within said main casing and a portion projecting forwardly therefrom and surrounding the forwardly projecting portions of said fingers, and a nose piece detachably secured to said main casing and extending forwardly 30 from the forward end thereof and enclosing the forwardly projecting portions of said fingers and clamping ring.

13. A mechanical pencil comprising a casing having a nose tapered toward its forward end, 40 said nose having therein a cavity having a portion tapered toward said forward end with the smaller end of said tapered portion of said cavity closely adjacent said forward end of said nose, lead grasping means mounted for forward 45 and backward reciprocation within said casing, said grasping means including a plurality of fingers movable laterally toward and away from a lead and having terminal portions tapered toward their forward ends so that when said fingers are reciprocated forwardly said terminal 50 portions may lie within said tapered portion of said cavity closely adjacent said forward end of said nose, said fingers also having, rearwardly of said terminal portions, other portions conically tapered toward their rearward ends and relieved suddenly at their rear ends, and a clamping ring surrounding said fingers and having a conically shaped inner surface adapted to cooperate with said conically tapered portions of 55 said fingers to clamp said fingers upon a lead and to move off said conically tapered portions beyond their relieved rear ends to unclamp said fingers and free them for substantial movement away from a lead.

AUGUST LEISTENSCHNEIDER.
